F. C. MORTON.

TIRE MAKING MACHINE.

APPLICATION FILED MAR. 26, 1919.

1,315,981.

Patented Sept. 16, 1919.

UNITED STATES PATENT OFFICE.

FREDERIC C. MORTON, OF NEW HAVEN, CONNECTICUT.

TIRE-MAKING MACHINE.

1,315,981.

Specification of Letters Patent. Patented Sept. 16, 1919.

Application filed March 26, 1919. Serial No. 285,265.

To all whom it may concern:

Be it known that I, FREDERIC C. MORTON, a citizen of the United States, and resident of New Haven, Connecticut, have invented 5 new and useful Improvements in Tire-Making Machines, of which the following is a specification.

My present invention relates to tire building machines, and more particularly to the 10 stretching and applying of strips of fabric to build up the tire carcass on a forming core.

The objects and advantages of my device will be fully apparent from the following 15 specification and claims considered in connection with the accompanying drawings, wherein there is described and illustrated a practical embodiment of the invention.

In the drawings, throughout the several 20 views of which similar reference numerals designate corresponding parts:

Figure 1 is a plan view of the device; and

Fig. 2 is a side elevation.

25 The type of tire making machine which I have conventionally shown in the drawings is one quite generally used in commercial practice, embodying among its various essential elements an annular, motor driven, 30 forming core, and a stitcher mechanism suitably mounted for operation thereon.

The numeral 10 designates a forming core, mounted upon a base 11 and driven by a motor 12. 13 denotes generally a supply table 35 for the fabric plies used in the manufacture of the tire carcass. At the forward end of the table 13, and separate therefrom, is a revolving drum 14 mounted in suitable bearings 15 upon a support 16 which is pivotally 40 connected to a base 17, the support 16 being connected by a contractile spring 18 to an anchor post 19. Another drum 20, comprising an outer bearing surface 21 and a raised offset annular portion 22, is revolutely 45 mounted in bearings 23 on a support 24 of the table at the other end thereof. Passing over the two drums 14 and 20, and slightly above the surface of the table 13, is an endless belt 25 of non-extensible, non-stretchable 50 material, such as thin steel or the like, provided with perforations 26 at spaced intervals along its center line for the entire length of the belt. The spring 18 connected to the anchor post 19 tends to maintain the 55 belt 25 normally taut, as will be understood.

A brake arm 27, pivotally mounted on the

standard 24 and supporting a brake shoe 27' for contact with the offset portion 22, of the drum 20 is connected to a contractile spring 28, the latter being adjustably secured to the table support 24. 60

I also provide a dummy strip 29, at one end of which is fixedly attached a cross bar 30, provided on the under side thereof with a hook or button 31 adapted to fit into the 65 perforations 26 of the belt 25.

In the operation of my device a length of fabric is connected at one end to the dummy strip 29 as at 33, and the hook or button 31 of the cross bar 30 is inserted in one of the 70 perforations of the belt located so as to make the distance from said perforation to the top of the core 10 slightly greater than the combined length of the dummy strip and ply. The operator will then pull 75 the ply a short distance, (stretching it and imparting tension thereto), to bring it to the core and stick it thereon. Then, as the core is rotated to wind the strip of fabric thereon, the brake shoe 27' contacts under 80 tension with the offset portion 22 of the drum 20. Thus, the driven core 10, to which is connected the length of fabric, must pull against the tension created by the brake shoe 27' on the drum 20, resulting in the 85 proper tensioning or stretching of the fabric strip 32. Adjustment of the spring 28 regulates the degree of stretching or tensioning imparted to the fabric strip 32, as will be understood. 90

After the ply of fabric is wound on the forming core it is separated from the dummy strip and the latter is carried back by hand for similar use in laying on the succeeding plies. 95

What I claim is:

1. In combination with a tire making machine, a fabric supply table; a revolving drum located at each end of the table; an endless belt operable over said drums; and 100 means for retarding the forward movement of said belt.

2. In combination with a tire making machine, a fabric supply table; an endless belt adapted to travel immediately over the top 105 surface of said table; and means for retarding the forward movement of said belt.

3. In combination with a tire making machine, a fabric supply table; an endless belt of non-extensible material adapted to travel 110 immediately over the top surface of said table; means for maintaining said belt taut;

- means for attaching a ply of fabric to said belt; and means for retarding the forward movement of said belt.
4. In combination with a tire making machine, a fabric supply table; a revolubly mounted drum located at each end of the table and in the same horizontal plane; an endless belt adapted to travel over said drums and immedately over the top surface of said table; a dummy strip; means for attaching the dummy strip to said belt; and a brake shoe attachment on one of the drums for retarding forward movement of the belt.
5. In a tension device for tire making machines, a pair of spaced apart, revolubly mounted drums, an endless belt adapted to travel over said drums; means for attach-
- ing a ply of fabric to said belt; and means for retarding the forward movement of the belt.
6. In combination with a tire making machine, a driven core; a pair of spaced drums or rollers positioned in alinement with said core; an endless belt adapted to travel over said drums or rollers; means for attaching a fabric strip to said belt; and travel-tensioning means for said belt.
- In witness whereof, I have hereunto signed my name in the presence of two sub- 30 scribing witnesses this twelfth day of March, 1919.

FREDERIC C. MORTON.
